CLAIM

The ornamental design for a liquid detergent containing suspended beads in a portion of a container, as shown and described.

DESCRIPTION

FIG. 1 is a right view of a liquid detergent containing suspended beads in a portion of a container, embodying the new design;

FIG. 2 is a front view thereof;

FIG. 3 is a left view thereof;

FIG. 4 is a back view thereof;

FIG. 5 is a top view thereof; and,

FIG. 6 is a bottom view.

The broken lines, which define the bounds of the claimed design, form no part thereof.
